JOHN W. RHINE AND HENRY L. RHINE, OF FORT WAYNE, INDIANA; SAID HENRY L. RHINE ASSIGNOR TO SAID JOHN W. RHINE.

CHIROPRACTOR'S TABLE.

1,184,660.

Specification of Letters Patent. Patented May 23, 1916.

Application filed September 7, 1915. Serial No. 49,269.

To all whom it may concern:

Be it known that we, JOHN W. RHINE and HENRY L. RHINE, citizens of the United States of America, and residents of Fort Wayne, in the county of Allen and State of Indiana, have invented certain new and useful Improvements in Chiropractors' Tables, of which the following is a specification.

This invention relates to improvements in chiropractic tables, and the object thereof is to afford a table adapted for chiropractors' use so constructed that it may be folded so as to occupy a small space and be in convenient form for transporting.

The idea of the invention is to so construct the device that when extended for use it will afford all of the necessary requirements of a table of its character, and when folded will have the neatness, compactness and appearance of a case as is ordinarily used by a traveler.

The objects of the invention are accomplished by the construction illustrated in the accompanying drawings in which:

Figure 1 is a perspective view showing the device extended and in position for use; Fig. 2 is a similar view of the same in one of its various adjustments; Fig. 3 is a perspective view of one of the sections of the table in a partial state of collapse; Fig. 4 is a detail sectional view showing the manner of securing the legs to the table top; Fig. 5 is a detail sectional view of one of the hinged shelves with the brace and legs for supporting the same; and Fig. 6 is a detail sectional view of one of the hinged shelves showing one of the hooks for securing the brace-frame and a hinged lever for disengaging the latter from the shelf.

Similar characters of reference indicate corresponding parts throughout the several views and referring now to the same: (1) and (2) are sections adapted to form an inclosing case, there being fasteners (3) and (3') respectively on the edges of each section adapted for connection for holding the two cases together when in closed position. Fasteners (4) upon the opposite sides of the sections are provided for securing corresponding edges of the sections together. A handle (5) is also secured to one of the sections by means of which the device may be

carried when the two sections have been secured together by the fasteners.

In general each section is the counter-part 55 of the other and each consists of a box-like case, closed at the top and open at the bottom. Within each end of the case is hinged a pair of legs (6) and (7) respectively that are connected near their hinged ends by a 60 cross-piece (8), and within the case is provided a catch (9) adapted to engage the corresponding cross-piece when the legs are extended and thereby hold the same in extended position. Folding braces (10) are 65 also provided for holding the legs in extended position, the braces being secured at one end to the corresponding legs and at their opposite ends to the inner walls of the case. 70

In connection with the legs (7) of each section are supplemental legs (12), the same being secured together by means of bars (13) that are pivoted respectively at their opposite ends to the legs (7) and the supplemental legs (12). The legs and supplemental legs (12) are also connected together by means of chains (14) that are of such length as to admit of the supplemental legs being swung outwardly at their lower ends 80 from the legs to which they are attached. To the upper ends of each pair of supplemental legs (12) is hinged a shelf (15), and there is also hinged to the supplemental legs a brace-frame (16) adapted to engage at its 85 outer end a ledge (17) formed upon the under side of the corresponding shelf at the outer end thereof and support said shelf. Under each shelf is arranged a series of retracting springs (18) each of which is permanently secured at one end to a staple (19) driven into the shelf and removably secured at its opposite end to a hook (20) that also extends from the under side of the shelf. Hooks (21) are also arranged in connection 95 with the brace-frames (16) that are adapted for connection respectively with said springs when the latter are removed from connection with the corresponding hooks (20), the intention being that as occasion 100 arises the operator may disconnect any one of the springs from its hook (20) and connect it with the corresponding hook (21) on the brace-frame so that the brace-frame will

be drawn by the tension of the spring into position for supporting the shelf with which it is associated. When thus connected, the brace-frame, due to the draft of the spring, 5 tends to hold the corresponding shelf in its uppermost position. Hooks (22) extend from the bottom of each of the shelves (15) and engage the cross-piece (23) at the outer end of the brace-frame (16) and thus limit 10 the upward swing of the shelf.

Beneath each of the shelves (15) at the outer end thereof is hinged a lever (24), and the inner end of the lever has an elastic band or spring (25) attached thereto, the opposite end of the latter being also secured by means of a screw-eye (26) to the rear end of the shelf so that the tension of the rubber-band or spring tends to hold the lever in normal position. A spring (27) is secured 15 to the rear end of the lever (24) so that the same may be pulled downwardly by the operator with the effect that the lever (24) engages the cross-piece (23) on the brace-frame and forces the same from engagement 20 with the ledge (17) on the shelf.

In operating the device the sections are parted from each other by releasing the catches (3), (3') and (4), and the legs (6) and (7) of each section are turned to extended position and secured by the latches (9). The supplemental legs are also extended and the shelves are raised to the position shown in Fig. 1 and the springs (18) are disconnected from the hooks (20) 30 and attached to the hooks (21) on the corresponding brace-frame. When each section has thus been adjusted they are placed in juxtaposition with their shelves opposite each other. The patient is laid upon the table formed by the two sections thus arranged, and as the operator desires, either one or both of the shelves may be released from its supporting brace-frame by pulling downwardly upon the string (27) which has 35 the effect of swinging the lever (24) so as to bear downwardly against the cross-piece (23) at the end of the brace-frame and force the brace-frame from its engagement behind the ledge on the shelf, thus the weight of 40 the patient upon the shelf bears it downwardly against the tension of the springs that tend to draw the brace-frame into its normal supporting position.

What we claim is:

55 1. In apparatus of the class described, two sections adapted to form a containing case; means for securing said sections together; legs pivotally secured at each end of each section and adapted to fold therein; a supplemental pair of legs suitably connected with the legs at one end of each section; a shelf hinged to the upper ends of said legs; a brace-frame hinged to said supplemental legs and adapted to engage and support the outer end of the shelf; and a

tension device adapted to engage the shelf and brace-frame, said supplemental legs, brace-frame and shelf being adapted to fold together with the legs with which the supplemental legs are connected and be moved 70 into the section.

2. In a device of the class described, two sections adapted to be secured together and form a carrying case, each section having pivoted therein legs adapted to form supports therefor; a pair of supplemental legs; pivoted bars connecting the supplemental legs with the legs at one end of the section; chains forming connection between the latter legs and said supplemental legs to hold 75 the latter in normal operating position; a shelf hinged to the upper end of the supplemental legs; and a spring drawn brace-frame hinged to the supplemental legs and engaged with the shelf. 80

3. In apparatus of the class described, a case formed of two sections adapted to be secured together; legs pivotally secured within each of said sections for supporting the same, said legs being adapted to be 85 folded within the corresponding section; a pair of supplemental legs for each of said sections and having connection with the legs at one end of the corresponding section; a hinged shelf supported at the upper ends 90 of the supplemental legs of each section; and a spring actuated brace-frame in connection with the supplemental legs for supporting the shelf.

4. In apparatus of the class described, 100 two sections adapted to form a carrying case having means in connection therewith for securing the same together; pivoted legs for each section adapted to support the same when extended and to be folded therein; 105 supplementary legs for each of said sections having folding relation with the legs at one end of the corresponding section; a hinged shelf for each section supported at one end by the supplementary legs; and a 110 spring actuated brace-frame in folding connection with the corresponding supplementary legs and being adapted to support the outer end of the shelf hinged thereto.

5. In apparatus of the class described, a 115 section having supporting legs; supplementary legs having folding connection with the legs at one end of the section; a shelf hinged to the supplementary legs; a spring actuated brace-frame hinged to the supplementary legs adapted to engage and support 120 the shelf; and a lever hinged to the under side of the shelf and adapted to bear against and disconnect the engagement of the frame from the shelf.

6. In apparatus of the class described, a section having folding legs; a pair of supplementary legs having folding relation with the legs at one end of the section; a hinged shelf supported by the supple- 130

mentary legs and having a ledge upon its under side at the outer end thereof; a spring actuated brace-frame hinged to the supplementary legs and adapted to engage the 5 ledge and support the shelf; and hooks in connection with the shelf adapted to engage the frame and limit its upward movement.

In testimony whereof we affix our signatures, in presence of two witnesses.
